MACHINE FOR MANUFACTURING BAG
TUBES

Harry E. Townsend, Brooklyn, N. Y.; Title Guarantee and Trust Company, executor of said Harry E. Townsend, deceased, assignor to Bartlett Arkell, New York, N. Y.

Application July 1, 1933, Serial No. 678,644
Renewed December 2, 1938

49 Claims. (Cl. 93—81)

My invention relates to machines for use in the manufacture of bag tubes, and especially wound paper tubes for multiply bags that are commonly used for cement and other weighty substances.

5 One of the objects of my invention is to provide a machine of this character which is capable of producing wound bag tubes of uniform quality and strength economically and expeditiously.

10 Another of the objects of the invention is to provide a machine of the character indicated which is adapted to be easily adjusted or set to produce bag tubes of any desired number of convolutions or plies.

15 Other objects of my invention are to generally improve the construction and mode of operation of machines of the character indicated as will hereinafter appear.

The several features of the invention, whereby 20 the above-mentioned and other objects may be attained, will be readily understood from the following description and accompanying drawings, in which:

25 Figure 1 is a side elevation of a machine embodying features of the invention in their preferred form;

Fig. 2 is a sectional view, on an enlarged scale, taken on the line 2—2 of Fig. 1;

Fig. 3 is a front view of a portion of the machine;

Fig. 4 is a similar view of the remaining portion;

Fig. 5 is a sectional elevation taken on the line 5—5 of Fig. 1;

35 Fig. 6 is a detail sectional view on the line 6—6 of Fig. 1;

Fig. 7 is a sectional view taken on the line 7—7 of Fig. 1;

Fig. 8 is a detail plan view of notching cutters 40 shown in Fig. 7;

Fig. 9 is a central sectional view of the rear portion of the machine;

Fig. 10 is a detail side elevation, partly in section, of a web controlling device;

45 Fig. 11 is a detail side view of a portion of a cam and cam lever shown in Figs. 1, 9 and 22;

Fig. 12 is a sectional view, partly in elevation, also taken on said line 7—7 of Fig. 1;

50 Figs. 13 and 14 are detail plan and side views of one of the upper notch cutters and associated parts;

Figs. 15 and 16 are similar views of the cooperating lower notch cutter;

55 Figs. 17 and 18 are sectional elevations taken

respectively on the lines 17—17 and 18—18 of Fig. 1;

Fig. 19 is a detail end view of portions of web perforating devices;

Fig. 20 is a section taken on the line 20—20 of Fig. 19;

Fig. 21 is a fragmentary view of a perforated portion of the paper web;

Fig. 22 is a central longitudinal section of the machine forming a continuation of Fig. 9;

Fig. 23 is a section taken on the line 23—23 of Figs. 1 and 22;

Fig. 24 is a detail section taken on the line 24—24 of Fig. 22;

Fig. 25 is a sectional elevation taken on the line 25—25 of Fig. 23;

Fig. 26 is a section taken on the line 26—26 of Fig. 1;

Fig. 27 is a detail edge and side view of a glue disk shown in Figs. 1, 22 and 26;

Fig. 28 is a plan view of a portion of the paper strip or web showing the manner in which the glue is applied at the notched portions of the web;

Fig. 29 is a section taken on the line 29—29 of Fig. 1;

Fig. 30 is a detail section taken on the line 30—30 of Fig. 29;

Fig. 31 is a section taken on the line 31—31 of Fig. 29;

Fig. 32 is a section similar to Fig. 30 but showing parts in different positions;

Fig. 33 is a section taken on the line 33—33 of Fig. 29;

Fig. 34 is a section on the line 34—34 of Fig. 3;

Figs. 35 and 36 are diagrammatical views illustrating the severing of the paper web to form the tube strips;

Fig. 37 is a section taken on the line 37—37 of Fig. 3;

Fig. 38 is a section taken on the line 38—38 of Fig. 1;

Fig. 39 is a side view of a change speed gear box and gearing;

Fig. 40 is a section taken on the line 40—40 of Fig. 1;

Fig. 41 is a detail side view, partly in section, of one of the winding mandrels;

Fig. 42 is a right hand end view of the winding mandrel;

Fig. 43 is a section taken on the line 43—43 of Fig. 41;

Fig. 44 is an exploded perspective of certain parts shown in Fig. 41;

55

- Fig. 45 is a side view of the web-severing or chopping bar;
- Fig. 46 is a sectional end elevation of two winding mandrels, showing the chopping blade about to sever the web;
- Fig. 47 is a similar view but showing the mandrels in section;
- Fig. 48 is a section taken on the line 48—48 of Fig. 40;
- 10 Fig. 49 is a section taken on the line 49—49 of Fig. 48;
- Fig. 50 is a section taken on the line 50—50 of Fig. 40;
- 15 Fig. 51 is a section taken on the line 51—51 of Fig. 50;
- Fig. 52 is a detail sectional plan view of a forward portion of the machine;
- Fig. 53 is a section taken substantially on the line 53—53 of Fig. 3;
- 20 20 Fig. 54 is a fragmentary detail view of parts obscured in Fig. 53;
- Fig. 55 is a section similar to that of Fig. 53 but showing certain parts in a different position;
- 25 Fig. 56 is a view similar to Fig. 54 but with the parts in a different position;
- Figs. 57 and 58 are similar to Figs. 53 and 55, but with parts in a different position;
- Fig. 59 is similar to Figs. 54 and 56, but with parts in different positions;
- 30 30 Fig. 60 is a view similar to Figs. 53, 55, 57 and 58 but showing ejecting mechanisms after they have ejected tubes from mandrels;
- Fig. 61 is a view similar to Fig. 60 showing especially parts hidden in the latter figure.
- 35 Fig. 62 is a detail face view of the ejector pad and holder;
- Fig. 63 is a section taken on the line 63—63 of Fig. 62;
- 40 Fig. 64 is a detail plan view of a resetting block shown in Fig. 60;
- Fig. 65 is a section taken on the line 65—65 of Fig. 3;
- Fig. 66 is a section taken on the line 66—66 of Fig. 3;
- 45 Fig. 67 is an enlarged central section of certain parts shown in Fig. 3;
- Fig. 68 is a plan view of certain parts shown in Fig. 67;
- 50 Figs. 69 and 70 are central sections of the portion of the machine shown in Fig. 4;
- Fig. 71 is a section taken on the line 71—71 of Fig. 70;
- Fig. 72 is a side view of a completed bag tube;
- 55 Fig. 73 is an end view of the bag tube before it is flattened;
- Fig. 74 is an end view of the flattened tube; and
- Fig. 75 is a development of the tube strip.
- 60 The machine illustrated in the drawings is particularly adapted for use in forming the flat bag tube shown in Fig. 72. This bag tube comprises a paper strip 2 which is wound upon itself a plurality of times, the tube shown in the drawings having five convolutions or plies. The tube has the longitudinal edges of its convolutions secured together by lines of adhesive 3, and the inner and outer ends of the tube strip are respectively secured to the overlying and underlying plies by lines of adhesive 5 and 6. The securing of the ends of the strip to the overlying and underlying plies is such that the secured ends overlap so that the resulting tube is of five ply thickness and strength throughout. The ends 70 of the two sides of the flattened tube are provided with notches 4, the two notches being centrally located at opposite sides of the tube. The tube as thus formed may be closed at its ends in any suitable manner.
- In the machine illustrated in the drawings, the strip from which the bag tubes are formed is supplied to the machine in a roll 8 that is mounted on brackets 10 at the rear of the machine (Fig. 1). The strip or web as it is drawn from the supply roll passes over a tension roll 12, between guide rolls 13, and then between rotating devices 14 which form notches in the edges of the strip which provide the notches 4 in the completed bag tubes. The web then passes over a guide roll 16, in a reverse direction beneath a 15 guide roll 18, and then between feed rolls 20, (Figs. 1 and 9). From these feed rolls the web passes between rotating devices 22 which form a transverse line of perforations 24 (Fig. 21) therein, the line of perforations being spaced from the forward end of the web a distance corresponding to the length of the strip which is to be wound into a tube. The web passes over a suitable supporting table 26, and then between glue applying rolls 28 which apply the two lines of glue 3 (Figs. 28 and 75) to the underside of the strip adjacent each of its longitudinal edges. The lines of glue are of suitable length and so positioned so that the edges of the convolutions or plies in the wound tube are secured together, 30 the glue being omitted from lengths forming the innermost plies of the tubes. The web then passes between a second pair of glue-applying rolls 2 which apply a transverse line of glue 5 to the underside of the strip spaced a distance 35 from its forward end corresponding to substantially one convolution or ply of the tube to be formed, and then a transverse line of glue 6 slightly in advance of the perforations 24.
- The forward end of the web then passes to one 40 of a series of four winding mandrels 36 carried by a rotating turret 38. Each mandrel is provided with means, hereinafter described, for securing the forward end of the web thereto so that during the rotation of the mandrel the web 45 is wound upon itself thereon. Near the completion of the winding of the end of the web on one of the mandrels another mandrel is positioned by the turret into engagement with the underside of the web. The web securing devices 50 on this mandrel act to secure the web thereto, and immediately thereafter a breaking or chopping blade 40 strikes the top side of the web adjacent the line of perforations 24 so as to sever or break the web on said line. During the continued rotation of the turret, the first-mentioned mandrel completes the winding of the severed strip, means being provided comprising a brush 42 for insuring the proper winding of the remainder of the strip on the mandrel.
- The securing of the web to the second-mentioned mandrel previously to the severing operation, is such that when the strip is severed from the web the continued rotation of this mandrel causes the end of the strip to be wound thereon, 65 and the continued rotation of the turret moving the next succeeding mandrel into position to engage the underside of the web to repeat the operation.
- At the completion of the winding of each strip 70 on a mandrel, the mandrel is circumferentially contracted so as to permit removal of the wound tube, and suitable devices engage the tube so as to stop the rotation thereof with relation to the mandrel while the tube is in a predetermined an- 75

gular position, and to eject the tube from the mandrel in said position.

The ejected tube falls upon a belt conveyor 44 (Figs. 3 and 4) and, owing to the fact that the glue is in more or less moistened or soft condition, upon striking the conveyor, the tube flattens out more or less at its longitudinal central portion. This conveyor 44 moves the tube into engagement with an upwardly and rearwardly inclined conveyor 46 that then cooperates therewith to feed the tube forwardly and at the same time flatten it. From these conveyors 44 and 46 the tube is caused to pass over an upwardly inclined table 48 and drops from said table upon an endless belt 50. The flattened tubes are deposited on this belt in overlapping relation (Fig. 69), the forward ends of the tubes being closely spaced one behind the other. In this condition, the tubes are carried beneath an endless belt 52 that is caused to apply pressure to the tubes by means of pressure rolls 54 that engage the top surface of said belt, and rolls 56 that support the underside of the belt 50. During the passage of the tubes between the two pressure belts 50 and 52 the glue is allowed to dry, the completed tubes being discharged from the other end of the pressure belts ready to be operated upon by the usual end closing machine.

The web supply roll 8 is wound at the paper factory on a tubular core 58. In the machine, the ends of the core with the paper wound thereon are mounted on blocks 60 (Figs. 1, 5, 6 and 9) that are secured on a mandrel 62, the left hand block 60 being detachably secured to the mandrel by means of a set screw 64. The supply roll is held from endwise movement on the mandrel by flanges 66 on the supporting blocks 60. The ends of the mandrel are supported for turning movement in U-shaped recesses in the brackets 10. To replace the supply roll 8, the mandrel 62 is removed from the brackets 10, and the left block 60 removed from the mandrel. The mandrel and sleeves 60 are applied to the core 58 of the new roll of paper, and then the mandrel with the roll 45 is mounted in the brackets 10.

Means is provided for adjusting the supply roll axially both in initially applying the roll and during the operation of the machine to maintain it in proper alignment with the web feeding devices 50 of the machine. To accomplish this, a grooved collar 70 is secured on the mandrel 62, which receives a roll or pin 72 on the rear end of a yoke 74 that is in sliding engagement with the top side of one of the brackets 10, the rear end of the yoke resting upon the collar 70. By means of a screw 78 that extends through apertures in the arms of the yoke and is centrally screw-threaded through the adjacent bracket 10, the yoke may be moved and through the grooved collar 70 the supply roll may be shifted axially as required.

It is, of course, advantageous to use a roll of paper of the largest diameter with which the machine can be operated satisfactorily at high speed. In the present instance, the machine has been designed to operate with rolls up to 40 inches in diameter or even larger. When a roll of this diameter is used and the machine started quickly, there is considerable resistance to the initial rotation of the roll due to inertia. When this 70 resistance has to be overcome by the pull of the feed rolls on the web of paper, the strain on the web is liable to be too great and there is danger of it breaking. This is additionally true when a friction brake is used against the roll of paper or 75 the paper arbor to maintain tension, as in this

case, not only the inertia of the roll of paper must be overcome but the additional resistance of the frictional brake. To aid in overcoming the inertia of the roll and to provide an efficient brake that will operate only when it is desired to stop the rotation of the roll, or check its speed, the mechanism now to be described has been provided.

The paper roll 8 is engaged by a rubber covered roll 90 secured on a shaft 92 which has its 10 ends journaled in bearings in the upper ends of arms 94 (Figs. 9 and 17). The lower ends of the arms 94 are secured on a rock shaft 96, there being provision for slight lost motion of the arms on the rock shaft independently of each other to 15 allow the roll 90 to adjust itself to variations in the surface of the paper roll.

The roll 90 is driven in a direction to tend to cause the paper roll to unwind, but at a slightly less speed than the feed of the web through the 20 machine. The roll 90 is driven by gear 98 secured on one end of its shaft 92 which is engaged by the gear 100 on a short shaft 102 mounted in the right hand arm 94 viewing Fig. 17. The shaft 102 is driven by a chain 104 that passes over a 25 sprocket wheel secured on said shaft and a sprocket wheel loosely mounted on the rock shaft 96. The latter sprocket wheel is secured to another sprocket wheel loosely mounted on said rock shaft 96 which is driven by sprocket chain 30 106 passing over a sprocket wheel on a driving shaft 108.

The roll 90 is caused to apply pressure on the paper supply roll 8 through connection with a piston 110 mounted in a cylinder 112 which has 35 the outer end of its rod pivotally mounted on a shaft or rod 114 connecting the roll supporting arms 94. Pipe connections 116 and 118 are adapted to supply air under pressure to opposite ends of the cylinder 112, the air supply being 40 controlled by the valve member 130. As shown, the paper web 2 passes over a tension roll 12 having its ends mounted in the outer ends of arms 94 that are secured on a rock shaft 96. The arms 94 tend to be swung upwardly by means of 45 weights 87 suspended from the ends of arms 88 secured on the rock shaft 96, the movements of the arms 84 and tension roll 12 being limited by set screws 89 in position to be respectively engaged by the upper and lower sides of the left 50 hand arm 88. Prior to starting the machine, the parts described are in the relative positions shown in Figs. 9 and 10. With the valve 130 in the position shown, compressed air passes freely through this valve and the pipe 116 to the rear 55 end of the cylinder 112, while the forward end of the cylinder is open to the atmosphere through the pipe 118 and port 128 of the valve body. The roll 90 is therefore held with considerable pressure against the paper roll and is adapted to act 60 powerfully to overcome the inertia of the roll when the machine is started. Due to the fact that the roll 90 is driven at a slightly slower surface speed than the feed rolls 20, the web 2 between the paper roll and the feed rolls gradually 65 becomes shorter, because of which the tension roll 12 is slowly drawn downwardly.

To the rock shaft 96 is secured one end of an arm 136, connected by a link 134 to an arm 132 secured to the valve 130. As the roll 12 is drawn 70 downwardly by the shortening web 2 it acts, through the connections above described, to rotate the valve 130 in a clockwise direction. The first result of this is to close the port 128, shutting off communication between the forward end 75

of the cylinder 112 and the atmosphere. Next the thin blade-like upper portion of the valve passes to the right hand side of the port 128, viewing Fig. 10, thereby admitting compressed air 5 to the forward end of the cylinder 112 and cutting it off from the rear end, without however, materially releasing the pressure behind the piston. The result of this is to relieve the pressure of the roll 90 on the paper roll sufficiently to permit 10 the pull of the tension roll 12 to slightly accelerate the speed of rotation of the paper roll. As the tension roll 12 moves upwardly the valve 130 is rotated slightly in a counter-clockwise direction, whereby compressed air is re-admitted 15 to the rear end of the cylinder and cut off from the front end, and the roll 90 again pressed against the paper roll with sufficient force to check its accelerated speed.

During the normal operation of the machine 20 there is air under pressure in both ends of the cylinder 112, but the pressure is slightly greater, first in one end and then in the other, as the valve 130 is rocked back and forth by the movement of the tension roll 12. During such normal 25 operation the roll 90 is held lightly against the paper roll, but with such variation of pressure that the speed of rotation of the paper roll is intermittently accelerated by the pull of the tension roll and retarded by contact with the roll 90. If 30 the machine is suddenly stopped, while the diameter of the paper roll is still large, there is a tendency for the momentum of the roll to cause a certain amount of slippage between the surface of the roll and the roll 90. As a result of this the 35 tension roll 12 moves toward its high position and, in doing so, rotates the valve 130 toward the position shown in Fig. 10. As soon as the valve moves far enough to uncover the port 128 the forward end of the cylinder 112 is relieved of all 40 pressure, and there being full pressure behind the piston, the roll 90 is pressed against the paper roll with sufficient force to prevent the roll from overrunning.

In order that the roll 90 may be instantly responsive to the variations in pressure in the cylinder 112, the weight of the roll and its supporting arms 94 is counterbalanced by means of a weight 138 that is mounted on a rod secured to a sleeve 140 that is loosely mounted on a shaft 108. This 45 sleeve carries a sprocket wheel over which a chain 142 passes which also passes over a sprocket wheel secured on the arm-carrying rock shaft 96, the weight thus tending to maintain the rock shaft in a predetermined angular position.

50 When all of the paper of a roll has been used, the tension roll 12 swings to its highest position at the same time moving the valve 130 to the position shown in Fig. 10. With the valve in this 55 position, the roll 90 is pressed firmly against the mandrel 62 and must be retracted before the mandrel can be removed from the machine. By rotating the valve 130 through an angle of ninety degrees, pressure is transferred from the back end of the cylinder 112 to the forward end, causing 60 the roll 90 to be drawn back to its extreme rearward position and held in that position while a fresh roll of paper is being placed in the machine. By rotating the valve 130 back to its original position the roll 90 is brought into engagement with the paper roll and the machine is again ready for operation.

The shaft 108 which drives the pressure roll 90 as above described, is driven through connection 75 with a drive shaft 144 of the machine, the con-

nexion comprising bevel gears 146, shaft 148 and bevel gears 150 (Figs. 1 and 17).

The notching devices 14, above referred to, are carried by shafts 152 arranged one above the other. These devices (Figs. 1, 7, 8, 9 and 12 to 16) 5 comprise two sets of drums, each of the lower ones of which carries a cutting blade 154 and each of the associated upper ones carries a co-operating cutting blade 156. Each of the lower blades is secured in a recess in its drum by means of screws 158 that extend through elongated slots in the blade and are screw-threaded into apertures in the drum, the slots providing for adjustment of the blade longitudinally of the axis of the drum. The drum 14 that carries the lower 10 blade 154 is adapted to be angularly adjusted on the shaft 152 by means of adjusting screws 159 that engage opposite sides of a lug 161 projecting from the drum, the screws 159 being threaded through lugs on a collar 163 secured to the shaft 20 152. Such adjustment of the drum 14 provides for adjustment of the blade 154 longitudinally of its cutting edge. Each of the upper blades 156 is secured on a block 160 by means of screws 162 that extend through slots in the blade and 25 are screw-threaded into the block, the slots providing for adjustment of the blade axially of the drum. The block 160 is pivotally mounted on the reduced end of a rod 164 which extends through apertures in webs or partitions 166 in the 30 drum. Each rod 164 is guided during its longitudinal movement by anti-friction rollers 170 which engage opposite sides of a squared portion 168 of the rod, thus holding the blade from lateral movement. The rollers 170 are supported on 35 bracket members 172 secured to the outer side of the outer partition 166. Each blade 156 is held from turning by anti-friction rolls 174 mounted on the brackets 172 that engage the inner side of the blade adjacent its longitudinal edges. Each 40 blade 156 is pressed inwardly by means of a spring 176 coiled about the rod 164 between a collar 178 secured on the rod and a washer that engages the inner side of the outer partition 166. The movement of the plunger rod 164 in either 45 direction and hence the blade is limited by stop collars 180 secured on the rod at opposite sides of the inner partition 166.

Each of the upper blades 156 has its cutting edges convexly curved in an arc corresponding 50 to the notch to be cut, and the associated lower blade 154 has a similarly curved concave cutting edge with the outer portion of the edge sloping off as shown. The cutting edge of the upper blade is of slightly larger radius than the cutting 55 edge of the lower blade. The lower blade is set slightly in advance of the upper blade. As the two blades come into engagement during the rotation of the blade carrying drums, the advancing end portions of the cutting edges first 60 engage and then exert a more or less of a cam action on each other as the cutting edge of one blade moves across the cutting edge of the other, this being permitted by the spring 176. Such shearing action of the cutting blades insures 65 smooth cutting out of the notches as the two blades are rotated in contact with each other.

The lower feed roll 20 for the strip is secured on a shaft 182 which has its ends mounted in fixed bearings (Figs. 1 and 9). The upper feed 70 roll 20 is carried by a shaft 184 which has its ends journaled in swinging brackets 186 that are pivoted on a shaft 188. The upper feed roll is pressed downwardly at each end on the strip by means of a spring 190 coiled about a rod 192 75

and interposed between a block 194, through which the outer end of the rod extends, and a collar on the rod. This rod is pivotally connected by means of a pin 193 with the associated bracket 186. Each block 194 is pivotally mounted between arms 196 (Fig. 18) that are secured on a shaft 198 extending across the machine. One end of the shaft 198 carries a worm wheel 200 which is engaged by a worm on a vertical shaft 202 that is adapted to be turned by means of a hand-wheel 203 secured on the lower end thereof. By turning the hand-wheel the tension springs 190 may be varied as desired to vary the pressure of the upper feed roll 20. The spring connection with the upper feed roll 20 allows this roll to be swung upwardly clear of the lower roll to thread the web through the machine and then brought down on the lower roll with the two springs exerting exactly the same pressure as before.

The perforating devices 22 (Figs. 9, 18, 19 and 20) comprise drums that are carried by upper and lower shafts 204. The upper shaft 204 is mounted in fixed bearings in the machine frame. The lower shaft 204 has its ends mounted on the ends of arms 206 that have their other ends secured on a rock shaft 208. The shaft 208 is moved to raise and lower the lower perforating device 22 at predetermined intervals through connection with cams 210 secured on the ends of a shaft 212 (Fig. 11). The connection with each of the cams comprises an arm 214 which has one end loosely mounted on the rock-shaft 208 and its other end carries a cam roll that engages the cam. Associated with each of the arms 214 is an arm 216 which has one end secured on the rock-shaft 208 and has its other end bifurcated so as to extend at opposite sides of a lug 218 on the arms 214. Adjusting screws 219 are screw threaded through apertures in the bifurcated ends of the arm 216 with their inner ends abutting opposite sides of the lug 218. By turning the screws 219 the lower perforating device 22 may be adjusted vertically.

The lower perforating device or drum 22 is slotted to receive a perforating blade 220 which has a sectional saw-tooth edge of such form as to form slot-like perforations 24 in the strip as shown in Fig. 21. The blade 220 is secured between suitable blade holding bars 221, the ends of one of which has projecting ears 222 through which adjusting screw 223 extends. Each of the adjusting screws is mounted for turning movement in a lug 224 projecting from one end wall of the drum. By adjusting the screws either or both ends of the perforated blade may be adjusted radially of the drum.

The upper perforating device or drum 22 is provided with a slot 226 of slightly greater width than the width of the knife blade so as to receive the edge of the blade therein as it perforates the paper strip.

It will be understood that the lower drum 22 which carries the perforating blades is raised and lowered in proper timed relation so as to perforate the strip or web on transverse lines, spaced a distance apart corresponding to the length of the strips to be severed from the web to form the bag tube.

The notch cutting devices 14, the feed rolls 20, and the perforating devices or drums 22 are all driven from the shaft 108 above referred to (Figs. 1, 9 and 18). The shaft 108 carries a gear 228 which operatively engages a gear 230 that is loosely mounted on the rock shaft 208.

75 This gear 230 drives a corresponding gear 232

secured on the shaft 188. The gear 230 at one side engages a gear 234 secured on the perforating drum shaft 204 so as to drive said shaft, and at its other side engages a gear 236 secured on the shaft 182 which carries the lower feed roll. 5 The gear 232 drives a gear 238 secured on the shaft 204 that carries the upper perforating drum, and also drives a gear 241 secured on the shaft 184 that carries the upper feeding roll 20. The gear 236 through an idler pinion 242 drives a 10 gear 244 secured on the shaft 152. The upper shaft 152 that carries the upper notching device is driven at the same speed as the lower notching device by means of a gear 246 secured thereon that is operatively engaged by the gear 244. 15

The shaft 212 that carries the cams 210 for raising and lowering the lower perforating device, is driven from the main drive shaft 144 of the machine through a gear 248 secured thereon which through idler gear 249 is driven by a gear 20 250 that is secured on a shaft 252 (Fig. 18). This shaft 252 is driven through bevel gears 253 by a shaft 254 that in turn is driven by the main drive shaft of the machine through speed change mechanism hereinafter described. 25

The glue applying rolls 28 are carried by shafts 256 (Figs. 1, 22 to 29). The upper roll may be covered with rubber or other flexible material. The lower roll comprises two pairs of glue applying disks 258 suitably spaced to apply the lines of 30 glue 3 to the web. These disks 258 receive the glue on their peripheral surfaces by engagement with the surface of a roll 260 rotatably mounted on a shaft 262. The glue roll 260 rotates in contact with a roll 264 carried by a shaft 266 which 35 receives glue from a glue pan 268. The amount of glue delivered by the fountain roll 264 to the glue roll 260 and hence to the glue applying disks, may be varied by adjustment of a stripping roll 270 toward and from the surface of the roll 264. 40 To provide for this the ends of the shaft of the stripping roll are mounted on arms 272 which are pivotally mounted on a shaft 274. Each arm is provided with a tail piece, one side of which is engaged by an adjusting screw 276 and its other 45 side by a spring 278 coiled about a fixed rod 279 which extends loosely through an aperture in said tail piece. With this construction by turning the screws 276, the ends of the stripping roll 270 may be adjusted as desired toward and from the 50 fountain roll 264. The stripping roll 270 has flanges 280 on its ends which ride closely adjacent the ends of the fountain roll 264 so as to prevent any material quantity of glue from running over the edges of the glue roll. 55

The shaft 256 that carries the glue-applying disks 258 has its ends journaled in the ends of arms 282 that are secured on the rock shaft 262. The disks 258 are raised and lowered into and out of engagement with the web to apply the 60 line of glue in proper lengths and positions by means of cams 284 through cam arms 283 which are adjustably secured to the rock shaft 262 in the same manner as the cam arms 214, for raising and lowering the perforating device, are adjustably secured to the rock shaft 208, the provision for adjustment allowing either or both ends of the glue disk shaft 256 to be adjusted toward and from the web so as to permit proper contact. The outer one of each pair of 65 glue-applying disks 258 is provided with a cut-away portion 286 (Fig. 27) so as to leave a gap in the line of glue applied thereby when a notch in the edge of the web is reached.

The upper one of the glue-applying devices 32 75

for applying the transverse lines of glue 5 and 6 comprises a roll which is carried by a shaft 290 which has its ends journaled in fixed bearings (Figs. 22, 29 to 33). The lower device comprises disks 292 secured on a shaft 294 that has its ends mounted in the free ends of arms 302 that are secured on a rock-shaft 297. This rock-shaft is adapted to be turned to raise and lower the disk 292 by means of cams 298, the connections between the cams and rock-shaft 297 being the same including the provision for adjustment as the connections between the cams 284 and the rock shaft 262.

A glue-applying blade 300 has its ends secured in slots in the ends of arms 302 pivotally mounted on the shaft 294, the blade extending through clearance slots in the disks 292. Each arm 302 is connected by a link 303 with an arm 304 secured on a rock-shaft 306 that has its ends mounted for turning movement in apertures in the two disks 292. An arm 307, secured on one end of the rock-shaft 306, carries a cam roll which during the rotation of the shaft 294, is adapted to engage one or the other of two cam surfaces on blocks 308 secured on a bracket 310 of the machine frame.

This connection with the blade carrying arms 302 is for alternately shifting the position of the blade laterally. Such shifting of the blade is necessary in order that the lines of glue 5 and 6 (Fig. 75) applied by the blade shall be properly positioned as shown. The blade is moved to the position shown in Fig. 32 to apply the line of glue 5, and is moved to the position shown in Fig. 30 to apply the line of glue 6. It is necessary to position the line of glue 5 inwardly with respect to the inner ply to which it is applied, in order that the end of the inner ply will come in contact therewith when the tube is wound.

When the glue applying device is raised to the high position the glue bar 300 is in the position shown in Fig. 30 in which position it applies the glue strip 6 to the strip for one bag as shown in Fig. 75. The device remains in the high position during slightly more than one revolution, during which time the position of the bar is shifted as shown in Fig. 32. In this position, on the second revolution of the device, the bar applies the strip of glue 5 to the second paper strip as shown in Fig. 75. The device then starts to move to the low position and engagement of the cam roll on the arm 307 with the block 308 moves the bar forwardly to the position shown in Fig. 30. Then as long as the device is in the low position the roll on arm 307 passes between the two blocks 308 and 309 without engaging with either of them. For the next glue applying operation, which is to apply the strip of glue 6 the device is raised to the high position between the time the roll on arm 307 passes between the blocks 308 and 309 and the time when the bar 300 reaches the highest point in its revolution. With the device dwelling in the high position the block 309 is then in the path of the roll on arm 307 and causes it to again reverse the bar while the device is dwelling in the high position.

In order to hold the blade in the position moved, a spring-pressed detent 311 (Fig. 31) snaps into one or the other of two holding notches 312 in the end of an arm 314 projecting from one of the blade-carrying arms 302, this detent being carried by one of the disks 292. In order that the detent shall not be forced out of its holding notch when the blade comes in contact with the surface of a glue roll 316 hereinafter de-

scribed that applies glue to the surface of the blade, as the blade approaches this glue roll the outer end of the detent 311 rides on a fixed abutment 318 and remains in substantial contact therewith until the blade has moved out of contact with the glue roll.

The upper roll 32 of this glue-applying device is provided with two longitudinally extending grooves 301 that are so positioned that when the glue-applying blade engages the paper, it forces the paper slightly into one or the other of these grooves so as to form more or less of a depression in the paper for receiving the glue, but without such pressure as to cause the glue to be squeezed out, thus preventing it from spreading out beyond the line to which it is applied.

The means for supplying glue to the glue applying device 32 includes a glue roll 316 (Fig. 22), a fountain roll 317, a glue pan 318 and a stripping roll 319, which parts are of the same construction and arrangement as the corresponding parts of the means above described for supplying glue to the glue applying devices 28.

Each of the glue pans 268 and 318 is adapted to be raised and lowered with relation to its fountain roll, and to be moved into a position to permit easy removal from the machine. To provide for this, each pan is detachably set into a carrier 320 which is mounted to slide fore and aft of the machine on supports 322 that are secured by rods 324 to bars 326 that are mounted to slide vertically in guideways in the sides of the machine frame. These bars are provided with rack teeth that are engaged by pinions 328 on a shaft 330 which is adapted to be turned by means of a hand-wheel 331 on one end thereof. By turning the hand-wheel the glue pan may be raised and lowered as desired. The pan is held in the position moved by means of a pawl 332 (Fig. 25) which engages a ratchet wheel 333 secured on the shaft 330. This pawl is pivotally mounted on a lever 334 and is held in engagement with the ratchet wheel by means of a spring 335 which is connected with the pawl through a hand grip lever 336 and a link 337. The lever 334 is pivoted on the shaft 330 and is held in vertical position against a stop pin 338 by means of a spring 339. By depressing the hand grip lever 336 the pawl may be released from the ratchet wheel.

When the glue pan is lowered, it may be shifted to one side to permit it to be removed by turning a hand-wheel 340. This hand-wheel is secured on a shaft 341 that carries pinions 342 engaging racks suitably connected with the under side of the pan carrier 320. In Fig. 22 the glue pan 268 is shown in effective position, and the glue pan 318 is shown in position where it may readily be removed from the machine or refilled.

The glue supplying rolls 260, 264, 316 and 317 are driven independently of the rest of the machine, by means of an electric motor 344 (Fig. 29) so that when desired the glue supplying rolls may be started or stopped independently of the operation of the other parts of the machine. Each of the glue rolls 260 and 316 is driven by means of a sprocket wheel secured to one end thereof over which passes a sprocket chain 346 which also passes over a sprocket wheel formed on a sleeve 347 which is loose on the shaft 274. Another sprocket wheel is also formed on sleeve 347, which is operatively connected by a sprocket chain 348 with a sprocket wheel formed on a sleeve 351 loosely mounted on a

shaft 349. Another sprocket wheel is formed on the sleeve 351 which through a sprocket chain 350 drives each of the fountain rolls 264 and 317. The sprocket wheel carrying sleeves 351 on the two shafts 349 are connected to rotate together by means of a sprocket chain 352.

One of the sprocket wheel sleeves 351 is driven through a sprocket chain 354, speed reducing gearing (not shown) and a chain 353 by the shaft of the motor 344. By throwing the motor into and out of operation the two sets of glue supplying devices may be thrown into and out of operation as desired.

The glue applying devices or rolls 28 and 32 are similarly arranged and are driven through similar mechanism from the drive shaft 144 so that a description of the gearing for driving one of said devices will suffice for both. Each of these mechanisms comprises a vertical shaft 356 which has its lower end connected with the drive shaft 144 through bevel gears 358, and its upper end connected through bevel gears 359, one of which is secured to a sprocket that drives a sprocket chain 360 driving a shaft 362. The shaft 362 has two gears 363 and 364 secured thereon. The gear 363 operatively engages a gear 365 which is secured on the shaft that carries the upper member of each of the glue-applying devices 28 and 32. The gear 364 through an idler 366 and a gear 367 drives each of the lower glue-applying devices 28 and 32, the gears 367 being secured on the shaft of each device.

Each of the cam shafts 274 is driven through a gear 368 secured thereon which through an idler 369 is driven by a gear 370 on the shaft 349 which in turn is driven through bevel gears by the shaft 254. This shaft is adapted to be driven from the drive shaft 144 at four different speeds through change speed gears 371 that are adapted to be separately connected with the shaft 144 by means of a gear shift lever 373.

The drive shaft 144 is driven through bevel gears 372 (Fig. 3) by a shaft 374 which in turn is driven by a counter-shaft 376 (Fig. 38). Mounted on this shaft 376 are two clutch members or sleeves 377 and 378 which are adapted to be separately clutched to the shaft by means of a suitable sliding clutch 379 that is adapted to be operated by a hand lever 381. The sleeves 377 and 378 are in driving connection with the shaft 374 through sprocket chains 380. When the sleeve 378 is clutched to the shaft 376 the shaft 374 is driven at slow speed, this drive being utilized for testing purposes. When the sleeve 377 is clutched to the shaft 376, the shaft 374 is driven at high speed, this drive being used in the normal operation of the machine. The shaft 376 is driven by means of a sprocket chain 382 from the shaft of an electric motor 383.

The turret 38 is secured on a shaft 384 which has its rear end mounted in a bearing in a standard 386 and its forward end in a bearing in a standard 388 (Figs. 3, 37 and 40). The turret comprises two four-arm spiders 390 and 391 secured to the shaft 384. The spider 391 has the outer ends of its arms secured to the inner periphery of a ring 392 (Fig. 34) which is in the form of a track and rides on two rollers 394 on the machine frame so as to assist in supporting and steadyng the turret during the rotation thereof.

The mandrels 36 are mounted on hollow shafts 396 each of which is journaled in bearings in corresponding arms of the spiders 390 and 391, the mandrels being arranged adjacent the outer side 75 of the spider 391. The turret and the several

mandrels are all driven through connection with a counter-shaft 398, which is mounted in a change speed gear box 400 (Figs. 1, 3, 37 and 39). This counter-shaft is driven through gears 401 by the drive shaft 374.

In order to adapt the machine for winding either two, three, four or five ply bag tubes, it is necessary to vary the speed of operation of both the turret and the mandrels with relation to the feed of the paper to the mandrels, and it is necessary also to relatively vary the speeds of the turret and mandrels, and, therefore, different speed change mechanisms are employed between the counter-shaft 398 and the turret and mandrels. The change speed mechanism for the turret comprises four gears 402 (Fig. 3) secured on a shaft 403, and adapted to be separately connected with the counter-shaft 398 by a gear shift lever 404.

The change speed mechanism for driving the several mandrels comprises gears 406 (Fig. 39) secured on a shaft 407. Driving connection is adapted to be established between each of these gears and the counter-shaft 398 through gear shifting members 408, there being one of such members for each set of gears.

The driving connection between the change speed shaft 403 and the turret comprises a pinion 410 secured on said shaft that operatively engages a gear 411 secured on the rear end of the turret shaft 384.

The driving connection between the change speed shaft 407 and the mandrels comprises a pinion 412 secured on said shaft which operatively engages a gear 414 loosely mounted on the turret shaft 384. This gear 414 is secured to a larger gear 415, also loosely mounted on the turret shaft, which drives gears 416 respectively secured on the rear ends of the several shafts 396 of the mandrels.

Each of the mandrels is provided with end walls 418 having inwardly projecting hubs loosely mounted on the mandrel shaft 396, a cylindrical wall 420 extending between the end walls, and a sleeve 422 secured to the hubs of the end walls 418.

The mandrel is connected with the mandrel shaft 396 through a coiled spring 424 so that during the winding of the paper on the mandrel the spring is placed under tension, causing the paper strip to be placed under tension until the strip is severed from the web. The spring 424 is coiled about a bolt or rod 426 which extends through a collar 427, mounted to turn in the outer end of the mandrel shaft 396, and a collar 428 which is held from turning in the shaft through a tongue and slot connection with a block 429 secured in the shaft, the inner end of the rod being secured to the block 429 (Figs. 42, 43, and 44). The ends of the spring are respectively secured to the collars 427 and 428. The collar 427 is secured to the outer end wall 418 of the mandrel by means of a projecting arm 430 thereon. A stop collar 432 is secured on the outer end of the mandrel shaft and is provided with a projecting lug 434 which is arranged to engage a stop pin 436 on the outer end wall 418 of the mandrel. A collar 438 is adjustably secured on the collar 432 and is provided with a stop lug 439 spaced from the lug 434. The advantages of the spring connections between the winding mandrels and their shafts will be hereinafter further described.

The cylindrical wall 420 of the mandrel is divided longitudinally into four segmental parts (Figs. 40, 47 and 53). Each of these segments has inwardly projecting portions that are provided

with radial grooves 441 which are in sliding engagement with guide bars or ribs 440 radially secured to the inner sides of the end walls 418, the construction permitting all four segments of the cylindrical wall to be moved inwardly and outwardly to circumferentially contract and expand the mandrel.

The mechanism for thus moving the segments comprises two spaced ears or lugs 442 (Fig. 58) projecting radially inwardly from each end portion of each segment, and arranged at opposite sides of a lug 444 secured to the mandrel sleeve 422. The associated lugs 442 and 444 are provided with relatively inclined slots 445 through 18 which extends a roller 446 mounted on the ends of a fabricated rod 447. The slots 445 are so relatively inclined that upon shifting the rod 447 forwardly from the position shown in Fig. 40, the rollers 446 by engagement with the walls of 20 the slots move the segments inwardly, and upon shifting the rod 447 in the opposite direction the segments are moved outwardly.

The means for thus shifting the rod 447 in opposite directions, comprises pins 448 (Fig. 57) secured to the rods and to a collar 449 mounted to turn on ball bearings on collars 450 which are mounted for longitudinal movement on the mandrel shaft, the pins 448 extending through clearance slots in the mandrel sleeve 422. The bearing collars 450 are adapted to be shifted to shift the rods 447 by means of a rod 452 mounted to slide in the mandrel shaft 398 and provided with projecting pins 454 that extend through guide slots in said shaft and are secured to the bearing 35 collars 450.

The rod 452 is adapted to be moved in opposite directions by means of a piston 455 secured to the rod and arranged in a cylinder 456. The piston is moved rearwardly to contract the mandrel by compressed air, and is moved in the opposite direction to expand the mandrel by suction. To provide for this, a pipe 457 is in communication with the interior of the mandrel shaft back of the piston through a suitably formed chamber 458 which surrounds the mandrel shaft and is held stationary with relation to the shaft by being secured to the spider 390, the shaft being provided with one or more openings 459 leading into said chamber. Each pipe 457 has its other end in communication with an aperture 460 in a disk 462 secured on the turret shaft 384. The four apertures 460 are arranged to register with slots 463 and 464 (Fig. 48) in a valve ring 465 adjustably secured in a casing 466 secured to the 50 turret shaft's standard 388. The slot 463 is in communication with a compressed air supply through an opening 467. The slot 464 is in communication with suction means through an aperture 468.

It will be apparent that with the slots 463 and 464 suitably positioned with relation to the apertures 460 leading into the pipes 457, that during the rotation of the turret, each mandrel may be contracted and expanded as desired.

The extent of the outward movement of the segments of the mandrel, and hence the diameter of the mandrel when in expanded condition may be varied by adjustment of a stop screw 469 that is screw-threaded into a block 478 and 70 by the engagement of the end of the piston rod therewith limits the mandrel expanding movement of the piston. A dash-pot is provided for the piston comprising a collar secured on the end of the piston rod which works between the 75 block 478 and a block 477 secured in the man-

drel shaft, there being vent openings in the shaft suitably spaced from the inner ends of the blocks 478 and 477.

The securing of the paper to each mandrel preparatory to the winding operation comprises suction means which is applied through three rows of perforations 470 (Figs. 40 and 47) in one of the segments of the mandrel. Each row of perforations lead from an aperture 471 in the wall of the segment. The inner ends of these apertures 471, through apertures in the inner end wall 418 of the mandrel, are in communication with a chamber 472 formed by a plate secured to the outer side of said inner end wall of the mandrel. This chamber 472 leads through apertures 473 in the plate into an annular chamber 474 formed in a collar that is secured to the outer spider 391 of the turret. A pipe 475 connects this chamber 474 with an aperture 476 in the valve disk 462. The several apertures 478 are arranged 20 opposite a valve ring 479 which has a slot 480 that is in communication through an aperture 482 with a vacuum pump or other suction means, and is also provided with a vent 484 that is open to the atmosphere.

With this construction during the rotation of the turret, as each of the apertures 478 is brought into registry with suction slot 480 in the valve ring, suction is applied through the perforations 470 in the associated mandrel to secure the paper 30 to the mandrel. This suction is entirely relieved upon the valve openings 478 being brought into registry with the air vent opening 484.

Immediately before the chopping blade 40 engages the paper the advancing mandrel strikes 35 the under side of the web just back of the line of perforations and the suction is applied and pins 486 are projected. As the blade strikes the paper it forces the paper down so as to insure the paper being pierced by the pins and being 40 brought into tight engagement with the suction openings. The pins 486 are mounted to slide in apertures in the segment of the mandrel which contain the suction holes 470, these pins serving to securely hold the paper against the action of the chopping blade (Figs. 41, 46 and 47). The pins 486 are secured on a bar 487 which has its ends mounted to slide in grooves in blocks 488 secured to the inner sides of the end walls of the mandrel. The pins are adapted to be 45 projected and retracted by means of arms 490 that are secured to a rock shaft 492, the arms being connected with the pin carrying bar 487 through pin and slot connections. The rock shaft 492 has its ends mounted in apertures in the end 50 walls of the mandrel, and one projecting end of this rock shaft has a lever 494 secured thereon. This lever carries a cam roll 495 which before the mandrel is brought into engagement with the paper web, engages a cam surface formed on a block 497 secured to the machine frame to project the pins 486 to cause them to pierce the paper. Near the completion of one revolution of the mandrel after the operation of the chopping blade 40 to sever the paper, the cam roll 495 engages a cam surface on a fixed block 496 secured to the turret ring 392 which causes the pins to be retracted from the paper. The pins are held in their projected and retracted positions by a spring-pressed detent 498 which is adapted to snap into notches 499 in the end of one arm of the lever 494. Thus the pins 486 are projected through the cylinder by the engagement of the roll 488 with the cam block 497.

The chopping blade 40 (Figs. 3, 34, 45 and 47) 75

is secured to arms 500 that are carried by a rotating shaft 502. This shaft has its ends journaled in bearings in the machine frame and is driven through angle gears 504, bevel gears 505, 5 and a gear 506 which engages the large turret gear 411. Back lash of the arm carrying shaft 502 is prevented by a brake band 507 that embraces a disk on the shaft.

It will be apparent from the foregoing that at 10 the time the web is broken at the perforated line the suction holes in the following cylinder are in position to catch the end of the oncoming web. The circumferential speed of the cylinder is, however, greater than the speed of the 15 advancing web. There is, therefore a tendency for the paper to slip on the surface of the cylinder in spite of the suction. To prevent this the pins 486 are provided. They are in such position, at the time the paper is broken, that the 20 action of the breaker blade in breaking the paper causes the paper to be forced down on the pins at a distance of about one and one-quarter inches back of the perforated line.

Bow shaped members 508 of resilient sheet 25 metal are secured to the chopping blade 40 near the ends thereof as shown (Figs. 45 and 47), and are so formed and arranged as to engage the paper slightly before the blade. As the paper is broken on the line of perforations by the 30 chopping blade 40 and as the chopping blade continues its downward movement to clear the approaching mandrel, the members 508 by engagement with the severed end of the paper insures that such end is laid tightly down over the suction holes, thus insuring the end being held on the mandrel as the paper is wound thereon.

In order that the bag may be wound with the 35 inner and outer ends of the strip overlapping, as shown in Fig. 73, the stop screw 469, Fig. 40, is so adjusted that when the winding mandrel is in fully expanded condition it is of slightly smaller diameter than the diameters of the rolls that feed the web of paper forwardly thereto. 45 If the mandrel were rigidly secured to its shaft it would be impossible to drive the mandrel at the same surface speed of the paper and at the same time bring the suction holes 470 to the same angular position when the paper is broken at the perforated line. The difficulty of driving the mandrel at such a speed as to wind and properly tension the paper is further increased by the fact that as the strip is being wound on the mandrel the mandrel is moving in an 50 arcuate path. To overcome these difficulties the mandrels are loosely mounted on their shafts and each mandrel connected to its shaft by the coiled spring as previously described, the mandrel shaft being driven at a speed that would be 55 slightly too great if the mandrel were rigidly secured thereon. This construction however, permits the mandrel to rotate at a slightly slower speed than its shaft, while the strip is being wound, and at the same time provides the necessary 60 tension to cause the strip to be wound tightly.

In the illustrated machine, mechanism is associated with each of the mandrels for ejecting the bag tube from the mandrel after the winding thereof (Figs. 40, 52, 53, 54, 55, 57 to 65). Each of these mechanisms comprises a pad 510 of soft rubber or similar material which, as the 70 turret carries the mandrel and the tube wound thereon toward a horizontal position and the 75 mandrel and tube reach a predetermined angular

position, firmly engages the side of the bag tube and by frictional engagement stops the rotation of the tube on the mandrel, the mandrel being previously contracted. The pad then moves longitudinally of the axis of the mandrel to eject 5 the tube from the mandrel.

The pad 510 is secured on the end of an arm of a bell-crank 512 pivotally mounted on a piston rod 514 which extends through apertures in bracket arms on a block 516 that is mounted to 10 slide in a guideway on a bar 518 secured on corresponding arms of spiders 519 secured to the turret shaft 384. The pad 510 is firmly pressed toward the mandrel by means of a coiled spring 520 having one end connected to the lower arm 15 of the bell-crank 512 and its other end connected to the carrier block 516. The pad 510 is normally held a sufficient distance away from the mandrel as shown in Fig. 53 to provide clearance for the severed or outer end of the paper during the winding operation, by means of one arm 20 of a latch lever 522 engaging a pin 523 on the upper arm of the bell crank 512. This latch lever 522 is pivotally mounted on a shaft 524 mounted in the bracket arms of the carrier block 516. 25 The rear end of the latch lever 522 carries a cam roll 526 which when the carrier block 516 is in retracted position, as shown in Fig. 52, is positioned beneath the end of an arm 528 secured to a shaft 530 that is journaled in bearings in 30 bracket arms 531 on the guide-way bar 518. This rock shaft 530 carries an arm 532 having a cam roll on the end thereof which is adapted to engage a cam rise 534 on the periphery of the stationary valve member 466, the cam roll being 35 held in engagement with the periphery of said member by means of a coiled spring 536.

During the rotation of the turret when each mandrel reaches a predetermined position, the cam roll on the associated arm 532 engages the 40 cam rise 534 so as to rock the shaft 530 and cause the arm 528 to depress the cam roll 526, and thus release the latch lever 522 from the arm that carries the ejecting pad 510. The spring 520 immediately acts to carry the ejecting pad 510 toward the bag tube. When the pad reaches the 45 position shown in Fig. 55 in proximity to the tube, its movement is arrested by the engagement of a latch arm 538 with the pin 523 on the pad arm. During the continued rotation of the mandrel a block 540 carried by the inner end wall of the mandrel strikes the end of an arm 542, secured to the shaft 524, to release the latch arm 538 from the pin 523, thus allowing the pad to firmly strike against the periphery of the bag tube 50 and stop the rotation of the tube with relation to the mandrel. The initial movement of the pad into a position close to the mandrel reduces the tendency of the pad to rebound on striking the mandrel or tube. As the pad arm is thus finally 55 released, a pin 544 on one arm of a bell-crank 546 (Fig. 56) rides out from under a shoulder on a dog 547 pivoted on the bracket arms of the carrier block 516, allowing the dog to snap down into holding engagement with said pin (Fig. 61). This 60 bell-crank 546 is secured by a pin 548 to the lower arm of the bell-crank 512 that carries the ejecting pad, and upon holding engagement of the dog 547 with the pin 544 which occurs immediately upon impact of the pad with the tube, the 65 pad is held from outward movement. In this manner vibration of the pad owing to impact is effectively prevented.

In order that the bag tubes shall be flattened accurately, it is not only necessary that the tube 70

- be stopped from further rotation in the correct angular position with reference to the winding cylinder or mandrel but that the mandrel itself be in correct angular position with reference to the shaft on which the turret is mounted. There is, therefore, a slight dwell after the ejector pad engages the tube before the longitudinal stripping action is started by the tripping of the latch 572 by engagement of the cam roll on the arm 532 with the cam rise 574. The cam block in which the rises 534 and 574 are formed is adjustable on the periphery of the stationary valve 466 so that the exact time at which the sleeve is ejected may be controlled.
- 15 Upon the mandrel reaching said predetermined angular position with relation to the turret shaft, the pad 510 is moved longitudinally of the axis of the mandrel carrying the tube therewith by frictional contact and ejects the tube from the 20 end of the mandrel.
- As the pad rides off the outer end of the mandrel at the end of the ejecting movement, its movement toward the axis of the mandrel is limited by the engagement of a stop screw 549 on an arm secured to the bell-crank 512, with a pin 551 on the bracket arms of the carrier block 516 (Fig. 60). Preparatory to the return of the 25 pad to its initial position, during the continued rotation of the turret, the end of the dog 547 strikes a re-setting lug 550 secured to a standard on the frame of the machine so as to release the dog from the holding pin 544, and immediately thereafter a cam roll 552 on the bell-crank 546 engages a cam surface 554 adjacent the lug 550 which rocks said bell crank so as to swing the pad carrying arm outwardly to its retracted position, allowing the latch lever 522 to hook over the pin 523 and thus hold said pad arm in retracted position during the return movement of the carrier block 516. After the dog 547 clears the lug 550 it is held from locking engagement with the pin 544 by the engagement of said pin with a shoulder 555 on said dog.
- 45 The ejecting mechanism above described is held in reset position until the next bag tube is wound on the mandrel, whereupon the operation of said mechanism is repeated.
- The carrier block 516 that carries each ejecting mechanism is adapted to be actuated by the 50 piston rod 514 and piston 556 mounted in a cylinder 558 secured to the spiders 390 and 391. The rear end of each piston cylinder is in communication through a pipe 560 with an aperture 562 in the rotating valve member 462. This aperture is adapted to register with slots 564 and 565 in a stationary valve ring 566 (Figs. 40 and 48). The slot 564 is in communication through an aperture 568 with a compressed air supply, and the slot 565 is in communication through an aperture 569 with a vacuum pump or other suction means. When the aperture 562 registers with the compressed air slot 564, air pressure is built up behind the piston to cause the piston to advance until a roll or pin 570 (Fig. 52) carried by the carrier block 516 strikes the tooth of a pawl 572 whereupon the movement of the piston is arrested, the pressure continuing to be built up behind the piston. After, however, the ejecting pad 510 is entirely released so as to engage the bag tube, the cam roll on the arm 532 engages a cam rise 574 on the valve casing 466, which further rocks the shaft 530 so as to cause the end of an arm 576 thereon to strike a pin 577 on the latch member 572, and thus quickly release the

latch member from the stud or roll 570. The pressure built up behind the piston then quickly forces the piston outwardly to effect the desired ejecting movement of the pad and carrier. This movement of the piston and carrier is limited by engagement of the piston head with the outer end of the cylinder which may be lined with shock absorbing material. After the ejection of the bag tube from the mandrel, the valve aperture 562 comes into registry with the suction slot 10 565 in the valve ring, whereupon the piston is caused to return to its initial position, the inward movement of the piston being limited by a stop collar 578 secured on the piston rod which closely enters a recess in the end of the cylinder, the 15 entrapped air in the recess absorbing the shock of the retracting movement of the piston.

The brush 42 for wiping the severed end of each tube strip over the underlying plies to complete the winding (Figs. 3 and 34) extends the 20 length of the mandrel and is secured on the ends of arms 580 that are fixed on a rock shaft 581 mounted in brackets on the machine frame. An arm 582 secured to the rock shaft to which is connected a spring 583 which tends to turn the 25 rock shaft so as to move the brush toward the rotating mandrels, such movement of the brush being limited by the engagement of the arm 582 with a stop pin 584. This construction insures that the brush will tightly wipe over the severed 30 end of the bag tube strip as the turret carries the rotating mandrel past the brush.

The belt conveyors 44 and 46 (Figs. 3, 4, 65, 66, 67, 68, 69 and 70) are angularly arranged so that their rear ends are spaced a distance apart in 35 position to receive between them the bag tubes as they are ejected from the mandrels. Each conveyor comprises a plurality of belts arranged side by side which pass over pulleys 586. The pulleys associated with the conveyor 44 have their 40 ends mounted in side frame members 588 and 589, and the pulleys associated with the conveyor 46 have their ends mounted in frame members 590. The frame members 588 and 589 of the conveyor 44 are supported by longitudinally adjustable links 592 so as to allow for angular adjustment of the conveyor. The frame members 590 of the conveyor 46 are supported at their forward ends by adjusting screws 594 each of which extends through a lug on each frame member 50 and its lower end rests upon a lug 595 on each of the frame members 589 of the conveyor 44. The rear portion of the conveyor 46 is supported by upright arms 596 which at their upper ends support a shaft 597 which also has its ends journaled in the frame members 590, and their lower ends pivoted on a shaft 598 which has its ends journaled in bearings in the frame members 591. The arms 596 are made in sections which are adapted to be adjusted vertically so as to vary 55 the angular position of the conveyor 46. Also, said arms 596 may be swung about the shaft 598 to adjust the conveyor fore and aft by means of longitudinally adjustable links 599 connected with said arms 596. The several belts of each conveyor are provided with suitable tensioning devices comprising spring pressed tension rolls 600.

Both conveyors are driven from the shaft 598. The conveyor 44 is driven by a chain 602 which passes over sprocket wheels secured on the shaft 70 598 and the shaft of the forward pulley 586. The upper conveyor 46 is driven by a chain 604 which passes over sprocket wheels on the shafts 598 and 597. The latter shaft drives the forward pulley of this conveyor through a chain 75

605 which passes over sprocket wheels on the shaft 597 and a shaft 606 which drives the shaft of the forward pulley through gears 607.

The drive shaft 598 for the two conveyors is driven through gears 608 from a shaft 609 which in turn is driven by a chain 610 that passes over a sprocket wheel thereon and over a sprocket wheel on a shaft 611 that is driven through bevel gears 612 by the drive shaft 374.

10 The bag tubes as they are ejected from the mandrels and are deposited upon the lower conveyor 44 in more or less flattened condition with respect to their longitudinal centers as above described, are each carried by the conveyor 44 into 15 contact with the conveyor 46 which together serve to first tend to flatten the forward end of the bag tube and then to feed it outwardly through the space between the forward ends of the conveyors (the bag tube taking substantially 20 the form indicated by dotted lines in Fig. 67 as the forward end thereof is flattened as it emerges from the conveyors. As the glue that secures the plies of the bag together is in more or less softened condition at this time, the tubes are readily 25 flattened as they pass between the conveyors.

The bag tubes are ejected by the forward ends of the conveyors upon the upwardly inclined table 48 with sufficient momentum as to cause the tubes to be separately projected over the table 30 and upon the belt conveyor 50. The travel of the conveyor 50 with relation to the speed of delivery of the bag tubes is such that the tubes fall upon the conveyor in overlapping relation, as indicated in Fig. 69, the tubes passing between 35 the conveyors 50 and 52 in this relation.

The belt conveyors 50 and 52 comprise belts which are of slightly greater width than the width of the flattened bag tube. The belt conveyor 50 passes over pulleys 614 and the belt conveyor 52 passes over pulleys 616. The shafts of the pulleys 614 are mounted in fixed bearings, and the shafts of the pulleys 616 are mounted in vertically adjustable bearing blocks 617. The conveyor 50 has an idler roll or pulley 618 mounted in fixed bearings directly beneath the rear pulley 616 of the conveyor 52. The upper stretch of the lower belt conveyor 50 is supported by closely spaced rollers 56 of small diameter, the ends of the rollers being mounted in recesses 621 45 in the side frames. The lower stretch of the upper belt conveyor 52 is pressed downwardly upon the lower belt by corresponding rollers 54 which are respectively arranged directly above the rollers 56. These rollers 54 have reduced 50 ends which are mounted in vertical slots 623 so as to allow for up and down movement of the rollers.

The rear pulley 616 of the upper belt conveyor 52 and the idler pulley 618 of the lower belt conveyor are suitably spaced apart so as to allow the bag tubes arranged in overlapping relation as described to pass between the belts of the conveyors. The upper belt is of flexible or pliable material, and the pressure rollers 54 are of small diameter, and closely spaced, so that a substantial uniform pressure is applied on the bag tubes as they pass between the belts irrespective of variations in thickness of the overlapping tubes. I have found that satisfactory results may be secured with the belt 52 made of a rubber covered fabric of about three-sixteenths of an inch in thickness, and with the pressure rolls about one and one-quarter inches in diameter, and spaced about one and one-half inches apart between centers. The 75 length of the adjacent stretches of the belts is

sufficient so as to insure substantial drying of the paste or glue in the tubes, and the continuous pressure applied by the pressure rollers 54 insures that the pasted areas of the tubes are held under proper pressure during the drying.

The bag tubes when they leave the conveyor belts 50 and 52 are in suitable condition to be operated upon by the usual satchel ending machine, or the ends of the tubes may be closed in any other suitable manner.

10 The belt conveyors 50 and 52 are driven separately from the rest of the machine from an electric motor 624 so that when the machine is stopped the conveyor can be operated until the tubes between the belts are all run out. Driving 15 connection between the motor shaft and the lower belt conveyor comprises a chain 625 that passes over sprocket wheels on the motor shaft and a shaft 626. This shaft 626 through suitable gearing (not shown) drives a counter-shaft 628 20 which through a sprocket chain 629 drives a shaft 630 which in turn through a worm and worm wheel 631 drives the shaft of the forward pulley 618 of the lower belt conveyor 50. The upper conveyor 52 is driven through chain 632 25 which passes over sprocket wheels on the shaft of said pulley 618 and a shaft 633. The shaft 633 through a chain 634 drives a shaft 635 which through gears 636 drives a shaft 637. The shaft 637 drives the upper conveyor through a chain 30 638 that passes over sprocket wheels on the shaft 637 and the shaft of the pulley.

While the machine is shown in the drawings as set up to produce bag tubes of five convolutions or plies as illustrated in Fig. 72, the machine may 35 be easily adjusted to produce tubes of two, three or four plies and this may be accomplished if desired without varying the rate of feed of the web from which the tube strips are cut, thus insuring maximum production.

40 To adjust the machine to produce bag tubes of four plies, for example, the gear shift lever 373 is shifted so as to change the speed of the cams 210, 284 and 298 for respectively lifting the perforating device and lower glue rolls 28 and 32 45 into their effective positions. The perforating device and glue rolls are each thus lifted one for each bag tube strip, and their cams each make one revolution for each tube strip, the cams rotating once, for example, for each five revolutions 50 of the machine when five ply tubes are being made. The cams 210, 284 and 298 are made in adjustable sections so as to enable the effective operations of these devices to be timed properly. It is also necessary to vary the rotation of the 55 mandrel carrying turret so as to cause the mandrels to be presented in proper timed relation to the feed of the web. This is accomplished by shifting the gear shift lever 404. Also, to adapt the machine for producing four ply tubes the 60 speed of rotation of the mandrels is varied, which may be accomplished by shifting the gear shift lever 408.

It will be apparent that by making corresponding adjustments the machine may be easily set 65 up for the production of either two or three ply bag tubes.

As will be evident to those skilled in the art, my invention permits various modifications without departing from the spirit thereof or the scope 70 of the appended claims.

What I claim is:

1. In a machine for use in the manufacture of bag tubes of the class described, the combination of strip feeding and winding means com- 75

- prising a mandrel for winding the advancing end portion of the strip upon itself, means for forming a transverse line of perforations in the strip at a predetermined point in its travel to the 5 mandrel, and means for severing the strip on said line of perforations when a predetermined portion of the strip has been wound on the mandrel, said strip feeding means feeding the strip continuously.
10. 2. In a machine for use in the manufacture of bag tubes of the class described, the combination of strip feeding and winding means comprising a plurality of winding mandrels, means for securing the advancing end of the strip to one of the 15 mandrels whereby the strip is wound thereon, means for moving another of said mandrels into engagement with one side of the strip a distance back of the first-mentioned mandrel, means for severing the strip on a transverse line positioned 20 between said mandrels, and means for securing the severed end of the strip to the second-mentioned mandrel.
15. 3. In a machine for use in the manufacture of bag tubes of the class described, the combination of strip feeding and winding means comprising a mandrel for winding the advancing end portion of the strip upon itself, means for forming a transverse line of perforations in the strip at a predetermined point in its travel to the mandrel, and means for severing the strip on said line of perforations when a predetermined portion 25 of the strip has been wound on the mandrel comprising an impact member serving to break the strip on said line of perforations.
20. 4. In a machine for use in the manufacture of bag tubes of the class described, the combination of strip feeding and winding means comprising a plurality of winding mandrels, means for securing the advancing end of the strip to one of the mandrels whereby the strip is wound thereon, means for presenting another of said mandrels to one 25 side of the strip a distance back of the first-mentioned mandrel, means for severing the strip on a transverse line positioned between said mandrels, and means for securing the severed end of the strip to the second-mentioned mandrel comprising holding devices that pierce the strip previously to the completion of the severing operation.
30. 5. In a machine for use in the manufacture of bag tubes of the class described, the combination of strip feeding and winding means comprising a plurality of winding mandrels, means for securing the advancing end of the strip to one of the 35 mandrels whereby the strip is wound thereon, means for presenting another of said mandrels to one side of the strip a distance back of the first-mentioned mandrel, means for severing the strip on a transverse line positioned between said mandrels, and means for securing the severed end of the strip to the second-mentioned mandrel comprising holding devices that pierce the strip previously to the completion of the severing operation.
35. 6. In a machine for use in the manufacture of bag tubes of the class described, the combination of strip feeding and winding means comprising a plurality of winding mandrels, means for securing the advancing end of the strip to one of the 40 mandrels whereby the strip is wound thereon, means for presenting another of said mandrels to one side of the strip a distance back of the first-mentioned mandrel, means for severing the strip on a transverse line positioned between said mandrels, and means for securing the severed end of the strip to the second-mentioned mandrel comprising suction means and devices that pierce the strip previously to the severing operation.
45. 7. In a machine for use in the manufacture of bag tubes of the class described, the combination of strip feeding and winding means comprising a plurality of winding mandrels, means for securing the advancing end of the strip to one of the 50 mandrels whereby the strip is wound thereon, means for presenting another of said mandrels to one side of the strip a distance back of the first-mentioned mandrel, means for severing the strip on a transverse line positioned between said mandrels, and means for securing the severed end of the strip to the second-mentioned mandrel comprising holding devices that pierce the strip previously to the completion of the severing operation.
55. 8. In a machine for use in the manufacture of bag tubes of the class described, the combination of strip feeding and winding means comprising a plurality of winding mandrels mounted on the turret, means for securing the advancing end of the strip to one of the mandrels whereby the strip is wound thereon during the rotation of the turret, means for maintaining the portion of the strip passing to the mandrel under tension and in such position as to be engaged by another mandrel during the continued rotation of the turret, means for securing the strip to the second-mentioned mandrel, and means for severing the strip between the last two mentioned mandrels.
60. 9. In a machine for use in the manufacture of bag tubes of the class described, the combination of strip feeding and winding means comprising a plurality of winding mandrels mounted on the turret, means for securing the advancing end of the strip to one of the mandrels whereby the strip is wound thereon during the rotation of the turret, means for maintaining the portion of the strip passing to the mandrel under tension and in such position as to be engaged by another mandrel during the continued rotation of the turret, means for securing the strip to the second-mentioned mandrel, and means for severing the strip between the last two mentioned mandrels comprising a chopping blade engaging the strip adjacent said holding devices.
65. 10. In a machine for use in the manufacture of bag tubes of the class described, the combination of strip feeding and winding means comprising a plurality of winding mandrels mounted on the turret, means for securing one end of the strip to one of the mandrels whereby said end of the strip is wound thereon during the rotation of the mandrel, the portion of the strip approaching said mandrel being in such position that when a predetermined length of the strip has been wound on the mandrel another of said mandrels engages the strip, means for securing the strip to the second-mentioned mandrel, and means for severing the strip between said mandrels comprising a rotating chopping blade engaging the strip adjacent the second-mentioned holding devices and operating in an arc through the space between the mandrels.
70. 11. In a machine for use in the manufacture of bag tubes of the class described, the combination of strip feeding and winding means comprising a rotating turret, and a plurality of winding mandrels carried by the turret, means for securing the strip to the second-mentioned mandrel comprising holding devices that pierce the strip previously to the completion of the severing operation.

ing the advancing end of the strip to one of the mandrels whereby the strip is wound on said mandrel, and means acting automatically at the completion of the winding of a predetermined length of the strip on said mandrel for securing the strip to another of said mandrels, and thereafter severing the strip between the mandrels.

12. In a machine for use in the manufacture of bag tubes of the class described, the combination of strip feeding and winding means comprising a turret and a plurality of winding mandrels carried by the turret, means for rotating the mandrels and turret continuously, means acting automatically during the rotation of the turret and mandrels for progressively presenting predetermined length portions of the strip to the mandrels, severing said length portions from the strip and causing them to be successively wound on the mandrels to form tubes, and means acting automatically after the completion of the winding of each tube on its mandrel for stopping the rotation of the tube in a predetermined angular position and for ejecting the tube from the mandrel while holding the tube in said predetermined angular position.

13. In a machine for use in the manufacture of bag tubes of the class described, the combination of strip feeding and winding means comprising a turret and a plurality of winding mandrels mounted on the turret, means for rotating the turret and mandrels continuously, means acting during the rotation of the turret and mandrels for causing predetermined length portions of the strip to be successively wound into tubes on the mandrels, respectively, and means acting during the continued rotation of the turret and mandrels when each mandrel reaches a substantially predetermined point in the rotation of the turret for successively removing the tubes from the mandrels while each tube is held in a predetermined angular position.

14. In a machine for use in the manufacture of bag tubes of the class described, the combination of strip feeding and winding means comprising a rotating turret and a plurality of winding mandrels, each of said mandrels having its peripheral wall divided longitudinally into a plurality of segmental parts mounted for movement toward and from the axis of the mandrel, devices for thus moving said parts and for positively holding said parts in their outer position, and means for thus operating said devices comprising a fluid operable piston acting when moved in one direction to operate said devices to move said parts inwardly and when moved in the opposite direction to move said parts outwardly, and means for varying the limit of one of the strokes of the piston to correspondingly vary the outward movement of said parts.

15. In a machine for use in the manufacture of bag tubes of the class described, the combination of means for feeding a strip longitudinally at a predetermined rate of speed, a mandrel, means for securing the end of the strip to the mandrel whereby said end is wound on the mandrel during the rotation of the latter, and means for rotating the mandrel comprising a mandrel shaft and a spring connecting the shaft with the mandrel whereby the spring is placed under tension during the rotation of the mandrel to tension the strip as it passes from said strip feeding means to the mandrel.

16. In a machine for use in the manufacture of bag tubes of the class described, the combina-

tion of means for feeding the strip longitudinally at a definite speed, a rotating turret, and a plurality of mandrels carried by the turret, means for rotating each of the mandrels during the rotation of the turret comprising a mandrel shaft, and means comprising a spring connecting the shaft with the mandrel, means for securing one end of the strip to one of the mandrels whereby said end is wound on the mandrel during the rotation of the turret and whereby another mandrel is moved into position to engage the strip during the winding on the first mandrel, and means for securing the strip to the second-mentioned mandrel and for severing the strip between the mandrels.

17. In a machine for use in the manufacture of bag tubes of the class described, the combination of a mandrel, a hollow shaft on which the mandrel is mounted, and a spring having one end connected thereto and the other end connected with the mandrel for establishing driving connection between the shaft and the mandrel whereby during the rotation of the shaft the mandrel is yieldingly carried thereby and upon a drag being placed on the mandrel the tension of the spring is increased.

18. In a machine for use in the manufacture of bag tubes of the class described, the combination of strip feeding and winding means, comprising a turret and a plurality of mandrels mounted on the turret, means for presenting predetermined length strips to the mandrels successively whereby they are respectively wound on the mandrels during the rotation of the turret, a device acting automatically when a mandrel reaches a predetermined position with relation to the axis of the turret for engaging the bag tube and for removing it from the mandrel, means for thus actuating said device comprising a spring tending to move said device into holding engagement with the bag tube, a latching device for holding said tube engaging device out of engagement with the bag tube, means acting automatically to release said latching device to allow said engaging device to be carried by its spring into engagement with the bag tube when the mandrel reaches said predetermined position, and means for moving said device longitudinally of the mandrel upon engagement thereof with the bag tube to cause said device to remove the bag tube from the mandrel.

19. The construction according to claim 18 in which means is provided for preventing outward movement of said tube engaging device upon impact with the bag.

20. In a machine for use in the manufacture of bag tubes of the class described, the combination of strip feeding and winding means, comprising a continuously rotating turret and continuously rotating winding mandrels mounted on the turret, means for respectively presenting predetermined length portions of the strip to the mandrels during the rotation of the turret whereby they are successively wound on the mandrels, and an ejecting device associated with each mandrel acting automatically when the mandrel is carried to a predetermined point by the turret to remove the wound strip length from the mandrel.

21. In a machine for use in the manufacture of bag tubes of the class described, the combination of strip feeding and winding means comprising a continuously rotating turret and continuously rotating winding mandrels carried by the turret, means for presenting predetermined length portions of the strip successively to the

- mandrels to cause them to be respectively wound on the mandrels, and an ejecting device associated with each mandrel acting automatically when the mandrel reaches a predetermined point 5 in its travel about the axis of the turret and when the mandrel is in a predetermined angular position to engage the bag tube, hold it in said predetermined angular position, and remove it in said position from the mandrel.
- 10 22. In a machine for use in the manufacture of bag tubes of the class described, the combination of strip feeding and winding means comprising a continuously rotating turret and a plurality of continuously rotating mandrels carried by the turret, means for presenting predetermined length portions of the strip successively to the mandrels whereby they are respectively wound on the mandrels to form bag tubes, and an ejecting device acting automatically when each mandrel reaches a predetermined point in its travel about the axis of the turret and when the mandrel is in a predetermined angular position to engage the tube thereon to hold it in said predetermined angular position and then move longitudinally of the mandrel to remove the tube from the mandrel, and after it has removed the tube to return to its initial position for operation on the next tube that is wound on the mandrel.
- 15 23. In a machine for use in the manufacture of bag tubes of the class described, the combination of strip feeding and winding means comprising a turret and a plurality of winding mandrels carried thereby, means for presenting predetermined length portions of the strip successively to the mandrels whereby they are respectively wound on the mandrels to form tubes, a tube ejecting device associated with each mandrel acting automatically when the mandrel reaches a predetermined point in its travel about the axis of the turret to move into holding engagement with the bag tube, a carrier for said ejecting device mounted to move longitudinally of the mandrel to cause the ejecting device to remove the tube from the mandrel when the ejecting device is in holding engagement with the tube, a fluid operable piston, and connections between the fluid operable piston and said carrier for moving the carrier in said direction.
- 20 24. In a machine for use in the manufacture of bag tubes of the class described, the combination of strip feeding and winding means comprising a turret and a plurality of winding mandrels carried thereby, means for presenting predetermined length portions of the strip successively to the mandrels whereby they are respectively wound on the mandrels to form tubes, a tube ejecting device associated with each mandrel acting automatically when the mandrel reaches a predetermined point in its travel about the axis of the turret and when the mandrel is in a predetermined angular position to move into holding engagement with the bag tube, a carrier for said ejecting device mounted to move longitudinally of the mandrel to cause the ejecting device to remove the tube from the mandrel when the ejecting device is in holding engagement with the tube, a fluid operable piston, and connections between the fluid operable piston and said carrier for moving the carrier in said direction, a piston cylinder, means for establishing communication between the piston cylinder at one side of the piston and a compressed air supply when the turret reaches a predetermined angular position where- 5 by the piston is moved in said direction, a latch for holding the piston from movement in said direction so as to permit pressure to be built up at said side of the piston, and means acting automatically to release said latch upon said ejecting device being moved into holding engagement with the wound tube.
- 25 25. In a machine for use in the manufacture of bag tubes of the class described, the combination of strip feeding and winding means comprising a continuously rotating turret and a plurality of continuously rotating mandrels carried by the turret, means for presenting predetermined length portions of the strip successively to the mandrels whereby they are respectively wound on the mandrels, and an ejecting device acting automatically when each mandrel with the portion of the strip wound thereon reaches a predetermined point in its travel about the axis of the turret and when the mandrel is in a predetermined angular position to engage the bag tube to hold the bag tube in said predetermined angular position and then move longitudinally of the mandrel to remove the bag tube from the mandrel, and after it has removed the tube to return to its initial position for operation on the next tube that is wound on the mandrel, and means for thus moving the ejecting device longitudinally of the mandrel comprising a piston, a piston cylinder, means for establishing communication between the cylinder at one side of the piston and a compressed air supply when the turret reaches a predetermined angular position and thereafter shutting off communication between said end of the cylinder and the compressed air supply and establishing communication between said end of the cylinder and suction means, whereby the piston is reciprocated, and connections between said piston and said carrier.
- 30 26. In a machine for use in the manufacture of bag tubes of the class described, the combination of strip feeding and winding means comprising a continuously rotating turret and a plurality of continuously rotating mandrels capable of being circumferentially contracted and expanded carried by the turret, means for presenting predetermined length portions of the strip successively to the mandrels whereby they are respectively wound on the mandrels to form tubes, means acting automatically as each mandrel approaches a predetermined position with relation to the axis of the turret to contract the mandrel, an ejecting device acting automatically when the mandrel reaches said position and is in a predetermined angular position to engage the tube and hold it in said predetermined angular position and while holding it in said position removing it from the mandrel.
- 35 27. In a machine for use in the manufacture of bag tubes of the class described, the combination of strip feeding and winding means comprising a plurality of continuously rotating winding mandrels, means for securing the forward end of the strip to one of the mandrels whereby the strip is wound thereon, means for presenting another of said mandrels to one side of the strip a distance back of the first-mentioned mandrel, means for securing the strip to the second-mentioned mandrel, and means for thereafter severing the strip between said mandrels and adjacent said securing means, and means for guiding the severed end portion of the strip of the first-mentioned mandrel to cause it to be tightly wound to complete the winding of the strip on said mandrel.
- 40 28. In a machine for use in the manufacture of bag tubes of the class described, the combination of strip feeding and winding means comprising a continuously rotating turret and a plurality of continuously rotating mandrels carried by the turret, means for presenting predetermined length portions of the strip successively to the mandrels whereby they are respectively wound on the mandrels to form tubes, means for establishing communication between the piston cylinder at one side of the piston and a compressed air supply when the turret reaches a predetermined angular position and thereafter severing the strip between said mandrels and adjacent said securing means, and means for guiding the severed end portion of the strip of the first-mentioned mandrel to cause it to be tightly wound to complete the winding of the strip on said mandrel.

of bag tubes of the class described, the combination of means for feeding a strip longitudinally, means for applying paste to one side of the strip as it is being fed, a rotating turret, a plurality of mandrels carried by the turret, means for successively presenting predetermined length portions of the strip to the mandrels, respectively, whereby said length portions are wound on the mandrels to form bag tubes, means for successively ejecting the wound tubes from the mandrels, devices operating to successively flatten the tubes ejected from the mandrels, and a conveyor for receiving the flattened tubes, said conveyor operating in timed relation to said devices so as to cause the flattened tubes to be received on the conveyor in overlapping relation, and means for applying pressure to the pasted areas of the tubes while they are being conveyed by said conveyor and maintaining the pressure until the paste becomes set.

29. A construction according to claim 28 in which the flattening means comprises endless belts angularly arranged so as to position their rear portions in spaced relation to receive the bag tubes between them and their forward portions in close proximity.

30. A construction according to claim 28 in which the flattening means comprises endless belts angularly arranged so as to position their rear portions in spaced relation to receive the cylindrical bag tubes between them and their forward portions in close proximity, and in which the conveyor comprises an endless belt positioned below the delivery ends of the flattening means and operating in timed relation thereto.

31. The combination of means for feeding a web longitudinally, devices for severing the web into predetermined length strips, means for successively winding the strips severed from the web into multiply tubes, and means for varying the time of effective operation of said strip severing means with relation to speed of operation of said strip feeding means to vary the lengths of the strips severed from the web.

45 32. In a machine for use in the manufacture of bag tubes of the class described, the combination of means for feeding a web longitudinally, devices for severing the web into predetermined length strips means for successively winding the strips severed from the web into tubes, and means for varying the time of effective operation of said severing devices with relation to the speed of operation of said feeding and winding means to vary the length of the strips severed from the web and the number of plies in the tubes.

33. In a machine for use in the manufacture of bag tubes of the class described, the combination of means for feeding a web longitudinally, devices for severing the web into predetermined length strips and for applying glue across one end of each strip length, means for successively winding the strips into tubes with the outer end of each strip secured by said glue to the underlying convolution of the tube, and means for varying the time of effective operation of said severing and gluing devices with relation to said feeding means.

70 34. In a machine for use in the manufacture of bag tubes of the class described, the combination of means for feeding a web longitudinally, devices for severing the web into predetermined length strips, a rotating turret, rotating mandrels carried by the turret, means for successively presenting the strips to the mandrels as they are carried by the turret to cause them to be wound

on the mandrels, and means for varying the speed of rotation of the turret and the speed of rotation of the mandrels independently of each other and with relation to the speed of operation of said feeding means.

5

35. In a machine for use in the manufacture of bag tubes of the class described, a rotating turret, a plurality of mandrels carried by the turret, means for successively presenting strips to the mandrels whereby they are successively wound on the mandrels, and means for relatively varying the speed of rotation of said turret and mandrels.

36. In a machine for use in the manufacture of bag tubes of the class described, the combination of means for feeding a web longitudinally, devices for severing the web into predetermined length strips, devices for successively winding the strips into tubes, and devices for ejecting the tubes from said winding devices while each tube is held in a predetermined angular position, the several devices being adapted to be adjusted to vary the number of convolutions in the completed tubes.

37. In a machine for use in the manufacture of bag tubes of the class described, the combination of strip feeding and winding means comprising a rotating turret and a plurality of winding mandrels, each of said mandrels having its peripheral wall divided longitudinally into a plurality of segmental parts mounted for movement toward and from the axis of the mandrel, devices for thus moving said parts and for positively holding said parts in their outer position, and means for thus operating said devices comprising a fluid operable piston acting when moved in one direction to operate said devices to move said parts inwardly and when moved in the opposite direction to move said parts outwardly.

38. In a machine for use in the manufacture of bag tubes of the class described, the combination of means for feeding a strip longitudinally at a definite speed, a continuously rotating turret, and a plurality of continuously rotating mandrels carried by the turret, means for securing one end of the strip to each of the mandrels successively when the mandrel is in a definite position whereby said end is wound on the mandrel during the rotation of the turret and whereby another mandrel is moved into position to engage the strip during the winding of the first mandrel, and means for maintaining uniform tension in the strip between the said feeding means and the mandrel as the strip is wound thereon.

39. In a machine for use in the manufacture of bag tubes of the class described, the combination of means for feeding a web longitudinally, means for cutting off predetermined length strips from the web, and means for winding them into multiply tubes of such diameter with relation to the length of the strips that each tube has a predetermined number of plies or convolutions with the ends of each tube strip overlapping.

40. A structure according to claim 39 in which means is provided for applying adhesive to each strip previously to the completion of the winding thereof to cause the overlapping inner and outer ends of the tube strip to be respectively secured to the overlying and underlying plies.

41. A structure according to claim 39 in which the means for winding the strips comprises a plurality of mandrels for successively receiving the strips, and a rotating turret on which the mandrels are mounted for successively moving them into position to receive the strips.

75

42. In a machine for use in the manufacture of bag tubes of the class described, the combination of means for feeding a web longitudinally at a definite speed, a continuously rotating turret, a plurality of continuously rotating mandrels carried by the turret, means for securing one end of the web to one of the mandrels when the mandrel is carried by the turret into a definite position and the mandrel is in a predetermined angular position whereby said end is wound on the mandrel during the continued rotation of the turret, and whereby another mandrel is moved by the turret into said definite position and while in said position and said mandrel is in said predetermined angular position it engages the web, and means for securing the web at said point of engagement to the second-mentioned mandrel.
43. In a machine for use in the manufacture of bag tubes of the class described, the combination of means for feeding a strip longitudinally at a predetermined rate of speed, a mandrel, means for securing the end of the strip to the mandrel whereby said end is wound on the mandrel during the rotation of the latter, and means for rotating the mandrel comprising a shaft and means connecting the mandrel and the shaft whereby the mandrel is permitted to rotate at a slower speed while the strip is being wound, and to cause the mandrel to return to its original position relatively to the shaft on the completion of the winding of the strip.
44. In a machine for use in the manufacture of bag tubes of the class described, the combination of strip feeding and winding means comprising a plurality of winding mandrels, means for securing the advancing end of the strip to one of the mandrels whereby the strip is wound thereon, means for presenting another of said mandrels to one side of the strip a distance back of the first-mentioned mandrel, means for severing the strip on a transverse line position between said mandrels, and means for securing the severed end of the strip to the second-mentioned mandrel previously to the completion of the severing operation.
45. In a machine for use in the manufacture of bag tubes of the class described, the combination of means for feeding a web longitudinally, means for applying two lines of adhesive transversely of the web and in definite spaced relation, means for severing predetermined length strips from the web on lines having a definite relation to the transverse lines of adhesive, and means for winding the strips into multi-ply tubes, each tube having a predetermined number of plies or convolutions with the ends of each tube strip over-

lapping, the overlapping inner and outer ends of the strip being secured by said lines of adhesive to the overlying and underlying plies respectively on a line positioned between said overlapping ends.

46. In a machine for use in the manufacture of bag tubes of the class described, the combination of means for feeding a web longitudinally, means for cutting off predetermined length strips from the web, and a mandrel for winding said strips into multi-ply tubes, said mandrel having a diameter such that when the strips are wound thereon the inner and outer ends of the strip are in overlapping position.

47. In a machine for use in the manufacture of bag tubes of the class described, the combination of strip feeding and winding means comprising a continuously rotating turret and a plurality of continuously rotating winding mandrels mounted on the turret, means for securing the advancing end of the strip to one of the mandrels whereby the strip is wound thereon during the rotation of the turret, means for maintaining the portion of the strip passing to the mandrel under tension and in such position as to be engaged by another mandrel during the continued rotation of the turret, means for securing the strip to the second-mentioned mandrel, and means for severing the strip between the last two mentioned mandrels.

48. A structure according to claim 8 in which the severing means comprises an impact member which after engaging and severing the strip adjacent the second-mentioned mandrel passes forwardly and upwardly with relation to said mandrel so as to clear the mandrel during the continued rotation of the turret.

49. In a machine for use in the manufacture of bag tubes of the class described, the combination of strip feeding and winding means comprising a turret and a plurality of winding mandrels carried by the turret, means for rotating the mandrels and turret, means acting automatically during the rotation of the turret and mandrels for progressively presenting predetermined length portions of the strip to the mandrels, severing said length portions from the strip and causing them to be successively wound on the mandrels to form tubes, and means associated with each mandrel acting automatically after the completion of the winding of each tube on the mandrel for stopping the rotation of the tube in a predetermined angular position and for ejecting the tube from the mandrel while holding the tube in said predetermined angular position.

HARRY E. TOWNSEND.
